UNITED STATES PATENT OFFICE.

WILLIAM H. HARTLINE, OF TAMAQUA, PENNSYLVANIA.

SIGNAL.

SPECIFICATION forming part of Letters Patent No. 700,041, dated May 13, 1902.

Application filed December 12, 1901. Serial No. 85,626. (No model.)

To all whom it may concern:

Be it known that I, WILLIAM H. HARTLINE, a citizen of the United States of America, residing at Tamaqua, in the county of Schuylkill and State of Pennsylvania, have invented 5 certain new and useful Improvements in Signals, of which the following is a specification.

This invention relates to signals, and particularly to that class for use in connection 10 with cars and locomotives.

The object of the invention is to produce a signal which is automatically sounded to alarm an engineer or trainman when an obstruction on the track is encountered or when 15 a semaphore is set at "danger."

Furthermore, the object of the invention is to provide means to prevent the sounding of the alarm when the engineer is on guard and is aware of the condition of the signal, 20 such means comprising a hand-controlled valve which closes the fluid-pipe on which the signal is mounted.

Furthermore, the object of the invention is to produce a signal and its operating mechanism which can be actuated by a person at the side of the moving engine, and, finally, the object is to produce a device of the character noted which will possess advantages in points of simplicity, durability, and efficiency, providing at the same time comparatively inexpensive to produce and sustain. 25

With the foregoing and other objects in view the invention consists in the details of construction and in the arrangement and combination of parts to be hereinafter more fully set forth and claimed. 35

In describing the invention in detail reference will be had to the accompanying drawings, forming part of this specification, where- 40 in like characters denote corresponding parts in the several views, and in which—

Figure 1 is a view in elevation of an engine with the invention applied. Fig. 2 is a view in detail of the alarm and its connection. Fig. 45 3 is a view of the semaphore and trip. Fig. 4 is an enlarged detail of a fragment thereof.

In the drawings, 1 indicates the railroad-track; 2, a semaphore-post; 3, a semaphore-arm suitably pivoted and having a connection 50 4, by which it is swung into a practically horizontal position through the medium of the bell-crank lever 5, operated by a pull on a

wire 6 or the like connection strung to a watchman's tower.

A block 7, with a cam-surface 8, is slidable 55 on the plates 9, secured to cross-ties 10. The block has a yoke 11, to which is connected a link 12, said link being pivoted to the bell-crank lever 5. The parts are in such position that normally the block 7 is stationed a 60 distance from the rail; but when the semaphore-arm is elevated said block is moved closer to the rail in order that the signal-controlling lever may be actuated through its contact with the block, thus warning the engineer that the danger-signal is set against him. 65

When the semaphore-arm is released, it falls by gravity, and the bell-crank lever will assume its normal position and draw the block 70 7 from the rail.

The signal-controlling lever 13 is pivoted at 14 to the frame of a locomotive, preferably at the front, in order that obstructions may 75 actuate the lever when the front of the engine has reached them, that the engineer may have a warning. A rod 15 is pivoted to the upper end of the lever 13 and extends rearwardly to the cab. The length of the rod may be varied by the turnbuckle 16, or said 80 rod may be solid and made the desired length to suit the particular engine for which it is designed.

A short pipe 17 is tapped onto the train-pipe 18 of the air-brake system just under 85 the engineer's valve. The pipe 17 has a valve 19, which is under the control and in reach of the engineer. A second valve 20 is interposed in the pipe, and the rod 15 is pivoted to the handle of the valve, the parts being 90 so positioned that as the lever 13 contacts with the block or other obstruction the rod will be moved longitudinally toward the front of the engine, thereby partially rotating the valve-plug and permitting air from the train-pipe 95 to escape through the pipe 17 to a whistle 21 on the end of said pipe. When the engineer is aware of the danger-signal being set against him and does not want the alarm to sound, the valve 19 is closed, thus preventing the air 100 from reaching the lever-operated valve or the whistle.

If desired, a series of blocks may be connected by wires to work in unison with the

operation of a semaphore-arm. It will also be noted that other connections may be made for actuating or moving the initial block.

The construction, operation, and advantages will, it is thought, be understood from the foregoing description, it being noted that changes in the proportion and details of construction may be resorted to for successfully carrying the invention into practice without departing from the scope thereof.

Having fully described the invention, what I claim as new, and desire to secure by Letters Patent, is—

In a signal, a semaphore-post and its arm, a bell-crank pivoted to the post near the bottom, a cam-block slideable with relation to one of the rails of a railway-track, a yoke secured to the block, a link connected to the

yoke and pivotally connected to the bell-crank, means whereby the bell-crank operates to lift the semaphore-arm and move the block close to the rail, a tripping-lever carried by the engine operated by contacting with the cam-block, a pipe tapped in the train-pipe of an air-brake system, a whistle on the pipe, a valve in the pipe and a connection from the tripping-lever to the valve whereby said valve is opened when the lever is tripped as and for the purpose described.

In testimony whereof I affix my signature, in the presence of two witnesses, this 11th day of December, 1901.

WILLIAM H. HARTLINE.
